ATTORNEYS

UNITED STATES PATENT OFFICE.

AXEL ANDERSON, OF WAHPETON, NORTH DAKOTA.

SHARPENER.

Application filed June 7, 1923. Serial No. 243,979.

To all whom it may concern:

Be it known that I, AXEL ANDERSON, a citizen of the United States, and resident of Wahpeton, in the county of Richland and 5 State of North Dakota, have invented certain new and useful Improvements in Sharpeners, of which the following is a specification.

My invention relates generally to improvements in sharpeners, more particularly to sharpeners for chalk such as that used by tailors in marking fabric and it consists in the combinations, constructions and arrangements herein described and claimed.

15 An object of the invention is to provide a simple and efficient sharpening device which affords facilities for sharpening a piece of chalk or like object quickly and conveniently and which also embodies means for collecting 20 all the dust and particles produced by the sharpening operation so that such dust and particles are not permitted to fall upon articles adjacent to the sharpening device but may be disposed of in any suitable 25 and desired manner.

A further object of the invention is to provide a sharpening device of the character described which is not likely to get out of order easily or to cause a piece of chalk 30 which is being sharpened to be broken and which will last a long time in the service for which it is intended without requiring the repair or replacement of any of the parts thereof.

35 Other objects and advantages will be apparent from the following description, considered in conjunction with the accompanying drawing, in which—

Figure 1 is a perspective view showing 40 a sharpener embodying the invention,

Figure 2 is a longitudinal vertical section through the sharpener,

Figure 3 is a perspective group view showing a slide bar which is comprised in 45 the device, and the supporting and guiding member for the slide bar, and

Figure 4 is a perspective view of a chalk rest which is adapted to be carried by the slide bar.

50 In carrying out my invention, I provide a container or case designated generally 1 which includes a bottom 2, a pair of parallel vertically disposed sides 3 and a pair of vertically disposed parallel ends 4, all connected together in any suitable known manner to provide a compartment which is open

at its upper end and which may be closed by a lid 5 which is included in the case and is supported in any suitable known manner to slide in a horizontal plane to and from the 60 position illustrated in Figures 1 and 2. An elongated supporting member or bar 6 has a body portion which is substantially channel-shaped in cross sectional contour and is sufficiently long to span the space between the 65 inner walls of the ends 4, being provided with attaching portions 7 at the opposite ends thereof which are secured by screws 8 or like fastening devices to the ends 4 so that the body of the supporting member 6 70 will be supported in underlying parallel relation to the lid 5 and somewhat nearer to the plane of the lid 5 than to that of the bottom 2.

As hereinbefore stated, the body of the 75 supporting member 6 is channel-shaped in cross sectional contour and the flanges 9 thereof extend upwardly from the plane of the web of the body of the supporting member and prevent lateral displacement from 80 the supporting member of a slide bar 10 which is adapted to be partially inserted through an opening 11 in one of the ends 4 to slide in the direction of its length on the supporting member 6 between the flanges 9 85 of the latter.

The length of the slide bar 10 is greater than that of the case 1 so that one end portion of the slide bar protrudes from the case 90 through the opening 11 at all times and this 90 protruding end portion may be provided with an aperture 12 adapted to be engaged by the finger of a hand and the slide bar thus manipulated conveniently.

A pair of cutter blades 13 are carried up- 95 on the upper side of the portion of the slide bar 10 which extends interiorly of the case 1. Each of the cutters 13 is angular in cross sectional contour and includes a flat attaching portion 13^a and a blade portion 13^b 100 which is upstanding from one edge of the attaching portion. The attaching portion 13^a has lateral notches 14 in the side edge thereof through which screws 15 may be inserted into engagement with the slide bar 105 to secure the cutter 13 in a desired position upon the slide bar 10. The portion 13^b of each of the cutters has one end thereof inclined and beveled as indicated at 16 to provide a cutting edge and the attaching 110 portion 13^a also may have the end thereof corresponding to the inclined end of the

portion 13^b beveled as indicated at 17 to provide a cutting edge. The cutters 13 are arranged upon the slide bar 10 in substantially V-shaped formation, the portions 13^b converging nearly together along the longitudinal median line of the slide bar and the cutters 13 being nearer to each other at their ends which are provided with the cutting edges 16 and 17 than at their opposite ends. The cutters 13 may be moved relatively to each other to vary the distance between the adjacent ends of the cutters by loosening the screws 15, making the desired adjustment and then tightening the screws 15. It is to be observed that the cutting edges 16 of the two cutters 13 are oppositely beveled. The cutters 13 are arranged on the slide bar 10 with the cutting edges 16 in confronting relation to the end 4 which is provided with the opening 11 and the lower portions of the cutting edges 16 extend across an opening 18 which at all times overlies a relatively large aperture 19 in the body of the supporting and guiding member 6. An elongated opening 20 is formed through the lid 5 along the longitudinal median line of the latter and in vertical alignment with the longitudinal median line of the slide bar 10, whereby a vertical plane intersecting the slide bar 10 along its longitudinal median line and intersecting the slot 20 along its longitudinal median line will be located midway between the cutting edges 16 of the pair of cutters 13. Therefore, a piece of chalk 21 such as that used by tailors will be held in position to be engaged by the cutting edges 16 when the piece of chalk is inserted vertically through the elongated opening 20 to rest at its lower end upon the slide bar and the latter is slid to extended position. In order to guide the inserted end of the piece of chalk into engagement with the cutting edges 16 and to support the piece of chalk against strain when the slide bar is manipulated, a pair of longitudinally aligned V or trough-shaped guide rests 22 and 23 respectively are disposed upon the slide bar 10 at opposite ends of the cutters 13 and along the longitudinal median lines of the slide bars. The guide 22 has laterally extending attaching portions 22^a having slots 24 therein through which screws 25 may be projected into engagement with the slide bar and the guide 22 thus secured in adjusted position in respect to the cutting edges 16 of the cutters, the guide 22 being positioned between the cutting edges 16 and the end 4 which is provided with the opening 11. The sides of the V-shaped body of the guide 22 are undercut or rearwardly beveled at the ends thereof proximate to the cutting edges 16 as indicated at 26 so that the upper edge portions of the sides of the V-shaped body

of the guide 22 extend in overlying relation to the aperture 18. The guide 23 also has attaching portions such as indicated at 27 which are secured by screws 28 to the slide bar 10 so that the sides of the V-shaped body of the guide 23 extend between the upstanding portions 13^b of the cutters, the sides of the V-shaped body of the guide 13 being beveled at their ends, which are inserted between the cutter portions 13^b as indicated at 29. The beveled edge portions 29 lie close against the inner walls of the upstanding portions 13^b in adjacent relation to the cutting edges 16.

From the foregoing description of the various parts of the device, the operation thereof may be readily understood. The piece of chalk which is to be sharpened is inserted through the aperture 20 in the lid. Shallow depressions in the upper face of the lid extend laterally from the aperture 20 and are adapted to partially receive the fingers grasping the piece of chalk so that the latter may be held firmly when it has been partially inserted through the aperture 20 to rest at its lower end upon the guide 22 between the V-shaped sides of the body of the latter.

The case 1 is held immovable and the slide bar 10 is pulled outward, thereby moving the cutters 13 into contact with the inserted end portion of the piece of chalk, whereby the inserted end portion will be sharpened and the sharpened end portion will pass between the upstanding portions 13^b of the cutters between the sides of the V-shaped body of the guide 23 and along the latter. Practically all the particles which are cut from the piece of chalk during the sharpening operation will fall through the aperture 18 in the slide bar 10 and the opening 19 in the supporting member 6 to the bottom of the case. Such particles of the chalk and dust as may be pushed along the guide 23 in advance of the sharpened end of the piece of chalk fall through an opening 31 in the slide bar at the rear end of the guide 23 and thence through one of the openings 32 in the bottom of the body of the support 6 to the bottom of the case. The collected chalk particles may be disposed of subsequently in any desired manner.

It will be apparent that a piece of chalk such as that ordinarily used by tailors or any other similar object made of a friable material may be quickly and conveniently sharpened when my improved sharpening device is used in the manner described and that the sharpened end portion of the chalk or like article is not likely to be broken during the sharpening operation while at the same time all dust and like particles cut from the piece of chalk or like article during the sharpening operation are prevented from floating about in the air and falling upon

articles adjacent to the sharpening device but on the contrary are collected and may be disposed of subsequently.

Obviously, my invention is susceptible of embodiment in forms other than that illustrated in the accompanying drawing and I therefore consider as my own all modifications and adaptations of the form of the device disclosed herein which fairly fall within the scope of the appended claims.

Having thus described the invention, what I claim is:

1. A sharpening device comprising a case having a lid provided with an opening, said case having a lateral opening, a slide bar protruding from the lateral opening and movable in a path extending beneath said opening in the lid, and cutting means carried by said slide bar for engaging an object which has been inserted through said opening in the lid.
  2. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, and cutting means carried upon the upper side of said slide member.
  3. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, and cutting means carried upon the upper side of said slide member, said cutting means comprising a pair of cutters arranged in spaced relation and having cutting edges at one end thereof.
  4. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, and cutting means carried upon the upper side of the slide member, said cutter blades being disposed upon the slide bar with the cutting edges overlying the opening in the slide bar.
- an opening in the portion thereof which is supported for movement underneath the first named opening and said guiding and supporting member having an opening underneath the opening in the slide member, and a pair of cutter blades secured upon the slide member in spaced relation with respect to each other, said cutter blades having cutting edges at one end thereof positioned equi-distant from a vertical plane extending through the longitudinal median line of the slide member.
5. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, said slide member having an opening in the portion thereof which is supported for movement underneath the first named opening and said guiding and supporting member having an opening underneath the opening in the slide member, and a pair of cutter blades adjustably secured upon the slide member in spaced relation with respect to each other, said cutter blades having cutting edges at one end thereof positioned equi-distant from a vertical plane extending through the longitudinal median line of the slide member.
6. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, said slide member having an opening in the portion thereof which is supported for movement underneath the first named opening and said guiding and supporting member having an opening underneath the opening in the slide member, and a pair of cutter blades secured upon the slide member in spaced relation with respect to each other, said cutter blades having cutting edges at one end thereof positioned equi-distant from a vertical plane extending through the longitudinal median line of the slide member, said cutter blades being disposed upon the slide bar with the cutting edges overlying the opening in the slide bar.

7. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, said slide member having an opening in the portion thereof which is supported for movement underneath the first named opening and said guiding and supporting member having an opening underneath the opening in the slide member, and a pair of cutter blades secured upon the slide member in spaced relation with respect to each other, said cutter blades having cutting edges at one end thereof positioned equidistant from a vertical plane extending through the longitudinal median line of the slide member, said cutter blades being disposed upon the slide bar with the cutting edges overlying the opening in the slide bar, a substantially V-shaped guide secured upon the slide bar to extend along the longitudinal median line of the latter, one end of said V-shaped guide being in proximity to the cutting edges of said cutter blades, and a second substantially V-shaped guide partially disposed between said cutting blades and having one end thereof in proximity to the ends of the cutting blades having the cutting edges and terminating at its other end beyond the opposite ends of the cutting blades.

8. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, said slide member having an opening in the portion thereof which is supported for movement underneath the first named opening and said guiding and supporting member having an opening underneath the opening in the slide member, and a pair of cutter blades secured upon the slide member in spaced relation with respect to each other, said cutter blades having cutting edges at one end thereof positioned equidistant from a vertical plane extending through the longitudinal median line of the slide member, said cutter blades being disposed upon the slide bar with the cutting edges overlying the opening in the slide bar, a substantially V-shaped guide secured upon the slide bar to extend along the longitudinal median line of the latter, one end of said V-shaped guide being in proximity to the cutting edges of said cutter blades, and a second substantially V-shaped guide partially disposed between said cutting blades and having one end thereof in proximity to the ends of the cutting blades having the cutting edges and terminating at its other end beyond the opposite ends of the cutting blades.

9. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, said slide member having an opening in the portion thereof which is supported for movement underneath the first named opening and said guiding and supporting member having an opening underneath the opening in the slide member, and a pair of cutter blades secured upon the slide member in spaced relation with respect to each other, said cutter blades having cutting edges at one end thereof positioned equidistant from a vertical plane extending through the longitudinal median line of the slide member, said cutter blades being disposed upon the slide bar with the cutting edges overlying the opening in the slide bar, a substantially V-shaped guide secured upon the slide bar to extend along the longitudinal median line of the latter, one end of said V-shaped guide being in proximity to the cutting edges of said cutter blades, and a second substantially V-shaped guide partially disposed between said cutting blades and having one end thereof in proximity to the ends of the cutting blades having the cutting edges and terminating at its other end beyond the opposite ends of the cutting blades.

10. A sharpening device comprising a case having a lid provided with an opening, said case also having an opening in one end thereof, a guiding and supporting member having a horizontally disposed body extending within the case in the plane of the lower side of the second named opening and having a portion thereof extending in underlying relation to the first named opening, a slide member supported on said guiding and supporting member and protruding from the case through said second named opening, said slide member having an opening in the portion thereof which is supported for movement underneath the first named opening and said guiding and supporting member having an opening underneath the opening in the slide member, and a pair of cutter blades secured upon the slide member in spaced relation with respect to each other, said cutter blades having cutting edges at one end thereof positioned equidistant from a vertical plane extending through the longitudinal median line of the slide member, said cutter blades being disposed upon the slide bar with the cutting edges overlying the openings in the slide bar, a substantially V-shaped guide secured upon the slide bar to extend along the longitudinal median line of the latter, one end of said V-shaped guide being in proximity to the cutting edges of said cutter blades, and a second substantially V-shaped guide partially disposed between said cutting blades and having one end thereof in proximity to the ends of the cutting blades having the cutting edges and terminating at its other end beyond the opposite ends of the cutting blades.

upon the slide bar to extend along the longitudinal median line of the latter, one end of said V-shaped guide being in proximity to the cutting edges of said cutter blades, a second substantially V-shaped guide partially disposed between said cutting blades and having one end thereof in proximity to the ends of the cutting blades having the cutting edges and terminating at its other

end beyond the opposite ends of the cutting blades, said slide bar having an opening at the last named end of the second substantially V-shaped guide and said first named guiding and supporting member having an opening with which the last named opening of the slide bar is in register at times.

AXEL ANDERSON.
